UNITED STATES PATENT OFFICE

153,274

DESIGN FOR A MUSICAL INSTRUMENT

Winfield S. Frazeur, Mason, Mich.

Application October 20, 1947, Serial No. 142,027

Term of patent 3½ years

(Cl. D34—15)

To all whom it may concern:

Be it known that I, Winfield S. Frazeur, a citizen of the United States, residing at Mason, county of Ingham and State of Michigan, have invented a new, original, and ornamental Design for a Musical Instrument, of which the following is a specification, reference being had to the accompanying drawing, forming part thereof.

In the drawing:

I claim:

The ornamental design for a musical instrument, substantially as shown.

WINFIELD S. FRAZEUR.
